(57) **CLAIM**

The ornamental design for a smart chip housing, as shown and described.

DESCRIPTION

FIG. 1 is a perspective view from the top-left of the smart chip housing;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a perspective view from the bottom-right thereof;

FIG. 9 is a front, perspective view from the top-left of the smart chip housing within a holster; and,

FIG. 10 is a back, perspective view from bottom-right of the smart chip housing within the holster.

The features shown in broken lines are for the purpose of illustrating portions of the article that form no part of the claimed design.

1 Claim, 8 Drawing Sheets
